UNITED STATES PATENT OFFICE.

RUDOLPH RINGENBERG, OF WATERBURY, CONNECTICUT, ASSIGNOR TO SCOVILL MANUFACTURING COMPANY, OF WATERBURY, CONNECTICUT, A CORPORATION OF CONNECTICUT.

VANITY CASE.

Application filed February 12, 1927. Serial No. 167,621.

This invention relates to certain improvements in vanity cases and particularly to improvements in a combined article holder and spring catch for use with these cases.

5 In certain types of vanity cases, which are small boxes usually of metal, employed for packing toilet articles, such as powder and rouge, there are provided a body and a cover associated on a hinge, a catch being 10 provided for holding these parts in locked relation. In many of these boxes a mirror or other article is carried in one member of the box, a toilet preparation being carried 15 in the other member.

15 It is the especial object of the present invention to provide an improved hinge and catch construction for these boxes in which a fitment is provided, one part of which will act to secure an article in the box and the 20 other part of which will carry a spring catch, this fitment being provided with means for securing it in the box and including a hinge for uniting the body and the cover.

25 A further object of the invention is to produce a box of this type which shall have few parts and in which the fitment may be easily and quickly associated with the body and the cover so as to pivotally unite these 30 parts and which at the same time shall be sufficiently strong and durable for the use contemplated.

With these and other objects not specifically referred to in view, the invention 35 consists in certain novel parts, arrangements and combinations which will be described in connection with the accompanying drawings and the novel features pointed out in the claims hereunto appended.

40 In these drawings:

Figure 1 is a plan view of the improved box, the box being shown open;

Figure 2 is a side view of the improved fitment;

45 Figure 3 is a partly sectional and partly broken away view of the cover of the box;

Figure 4 is a side view of one part of the fitment;

50 Figure 5 is a similar view of the other part of the fitment.

Figure 6 is a partly broken away sectional view of the bottom of the box, and

Figure 7 is a plan view of the catch carrying member.

Referring now to these drawings, the improved box includes a cover part or member 1 and a body 2. The cover 1 is provided with a peripheral flange 3, which at its back is cut away as indicated at 4 to receive a hinge, hereinafter referred to. The front 60 of the wall is provided with an outstruck portion 5, leaving a recess 6 for engagement with a catch, also hereinafter referred to. The body 2 is formed with a peripheral wall 7, the rear end of which is cut away, 65 as indicated at 8, and the front of which is provided with a slot 9, the parts 8 and 9 being later on referred to. The side wall 7 is inset at 10 to form a flange 11 with which the wall 3 of the cover has telescopic engagement when the box is closed.

70 One of the members of the box, as the cover, is designed to carry an article, this article in the present instance being a mirror 12, and the cover and the body are locked 75 together by a spring catch, indicated generally by the numeral 13 in Fig. 1, and the body and the cover are pivotally associated.

In accordance with the invention, a fitment 80 is provided, which comprises an annulus or bezel for holding the mirror in place and a part or ring carrying the spring catch, these two members being formed with integral interengaging hinge knuckles, so that when the fitment is placed in the box it will pivotally associate the body and the cover, will 85 hold the mirror or other article in place, and will provide the spring catch for holding the parts together.

90 While the particular construction of this fitment may be somewhat varied as shown, it comprises an annulus or bezel 14 forming a downwardly extending flange 15, the bezel being provided with spaced hinge knuckles 16 formed by turning over a part 95 of the metal of the bezel. The other member is shown in the form of a strip 17, which is provided with spaced knuckles 18 formed by turning in the metal at the ends of the strip, and centrally between the ends the strip 100 is formed with a spring catch 19 formed integrally therewith, a manual release 20 being provided for manipulating the catch. It will be understood that this strip is made of resilient metal and may be bent 105 to a circular form to fit the box, being of a length substantially corresponding to the inside periphery of the member with which

it is placed, and when so bent the catch 19 is opposite the knuckle 18, and is sufficiently flexible to permit the catch to be moved so as to free it from the seat 6 of the cover. 5 The two parts of the fitment are secured together by a pin 21, which passes through the hinge knuckles 16, 18 and pivotally associates these two parts. This fitment is secured in the box, the annulus or bezel fitting into the cover, and the strip fitting into the body. Means are provided for securing these parts in the box so that they will lie securely in place and will thus act to hingedly unite the body and cover. 10 15 While these means may vary, in the particular construction illustrated, the walls of the cover are provided with inwardly extending projections 22 past which the annulus or bezel may be forced. As the annulus or bezel is dimensioned to have a snug frictional fit with the wall 3 of the cover, these indentations assist in holding it securely in place. The strip is held in place by its resiliency. To 20 provide for the reception of a compact or the like, the strip is, as shown, cut away at opposite sides to form recesses 23 past which a compact or the like may be sprung, these recesses being located, when the parts are assembled, at opposite sides of the box between the spring catch and the hinge. 25

When the box is closed, the catch 19 engages the recess 6 in the cover of the box, the nose of the catch extending through a slot 24 in the flange 11 of the body to permit this engagement. The manual release 20 extends through the slot 9 in the wall of the body, and by operating this release the catch may be freed. 30

With the construction described, a very simple and compact arrangement has been provided for pivotally associating the two parts of a box for holding an article in the spring and for providing a spring catch which is easily and quickly assembled and which provides a sufficiently strong structure for the uses contemplated. 35

While the invention is shown and described in its preferred form, it will be understood, of course, that various changes may be made in the particular construction of the bezel and strip, and the means for securing these parts in the box without departing from the invention as defined in the appended claims. 40

What I claim is:

55 1. In a vanity case, body and cover mem-

bers, a bezel in one of the members, a strip in the other of the members of a length corresponding to the inside periphery of the member, said bezel and strip having integral interengaging hinge knuckles, the knuckles 60 on the strip being arranged on the opposite ends thereof, a pin passing through the knuckles, and a spring catch carried by one of the parts for locking the body and cover together. 65

2. In a vanity case, body and cover members, a bezel in one of the members, of a length corresponding to the inside periphery of the member, a strip in the other of the members, a mirror held in place by the bezel, 70 hinge knuckles formed on the edges of the bezel and strip, the knuckles on the strip being formed on the opposite ends thereof, a pin uniting the knuckles, and an integral spring catch on the strip for locking the 75 body and cover together.

3. In a vanity case, body and cover members, a bezel in one of the members, a strip in the other of the members of a length corresponding to the inside periphery of the 80 member, a mirror held in place by the bezel, hinge knuckles integral with the strip and bezel, the knuckles on the strip being formed on the opposite ends thereof, a pin uniting the knuckles, means for holding the bezel in 85 engagement with the walls of the member in which it is placed, notches in the strip for permitting the reception of an article, and a spring catch on the strip for locking the body and cover together. 90

4. A combined article holder and catch for vanity boxes, comprising a bezel and a strip having integral interengaging hinge knuckles, a pintle passing through the knuckles, 95 said strip being of a length corresponding to the inside periphery of the member and having the knuckles thereon formed on the opposite ends thereof, and a catch integral with the strip.

5. A combined article holder and catch for vanity boxes, comprising a bezel having a flange, a strip having notches said bezel and strip having interengaging hinge knuckles, the knuckles on the strip being formed on the opposite ends thereof, a pintle passing 100 through the knuckles, and a catch carried by the strip. 105

In testimony whereof, I have hereunto set my hand.

RUDOLPH RINGENBERG.

CERTIFICATE OF CORRECTION.

Patent No. 1,669,842.

Granted May 15, 1928, to

RUDOLPH RINGENBERG.

It is hereby certified that error appears in the printed specification of the above numbered patent requiring correction as follows: Page 2, lines 67 to 69, claim 2, strike out the words "of a length corresponding to the inside periphery of the member", and insert the same to follow after the word "members" in line 70; same page, line 94, claim 4, strike out the words "a pintle passing through the knuckles" and insert the same to follow after the word "thereof" in line 98; and that the said Letters Patent should be read with these corrections therein that the same may conform to the record of the case in the Patent Office.

Signed and sealed this 19th day of June, A. D. 1928.

(Seal)

M. J. Moore,
Acting Commissioner of Patents.
